FIG. 5 is a side elevational view of the design of FIG. 1, the only difference being in the horizontal angle of the skirt;

FIG. 6 is a side elevational view of the design of FIG. 1, the only difference being in the near vertical angle of the skirt;

FIG. 7 is a side elevational view of the design of FIG. 1, the only difference being in the downward angle of the skirt;

FIG. 8 is a side elevational view of a second embodiment of the design of FIG. 1, the only difference being in the height of the base;

FIG. 9 is a side elevational view of a third embodiment of the design of FIG. 1, the only difference being in the height of the base;

FIG. 10 is a side elevational view of a fourth embodiment of the design of FIG. 1, the only difference being in the size of the skirt;

FIG. 11 is a side elevational view of a fifth embodiment of the design of FIG. 1, the only difference being in the size of the skirt;

(Description continued on next page.)

- FIG. 12 is a perspective view of a sixth embodiment of our new flower pot cover design;
FIG. 13 is a side elevational view thereof;
FIG. 14 is a top plan view thereof;
FIG. 15 is a bottom plan view thereof;
FIG. 16 is a side elevational view of the design of FIG. 12, the only difference being in the horizontal angle of the skirt;
FIG. 17 is a side elevational view of the design of FIG. 12, the only difference being in the near vertical angle of the skirt;
FIG. 18 is a side elevational view of the design of FIG. 12, the only difference being in the downward angle of the skirt;
FIG. 19 is a side elevational view of a seventh embodiment of the flower pot cover design, the only difference being in the height of the base;
FIG. 20 is a side elevational view of an eighth embodiment of the flower pot cover design, the only difference being in the height of the base;
FIG. 21 is a side elevational view of a ninth embodiment of the flower pot cover design, the only difference being in the size of the skirt;
FIG. 22 is a side elevational view of a tenth embodiment of the flower pot cover design, the only difference being in the size of the skirt;
FIG. 23 is a perspective view of an eleventh embodiment of our new flower pot cover design;
FIG. 24 is a side elevational view thereof;
FIG. 25 is a top plan view thereof;
FIG. 26 is a bottom plan view thereof;
FIG. 27 is a side elevational view of the design of FIG. 23, the only difference being in the horizontal angle of the skirt;
FIG. 28 is a side elevational view of the design of FIG. 23, the only difference being in the near vertical angle of the skirt;
FIG. 29 is a side elevational view of the design of FIG. 23, the only difference being in the downward angle of the skirt;
FIG. 30 is a side elevational view of a twelfth embodiment of the flower pot cover design, the only difference being in the height of the base;
FIG. 31 is a side elevational view of an thirteenth embodiment of the flower pot cover design, the only difference being in the height of the base;
FIG. 32 is a side elevational view of a fourteenth embodiment of the flower pot cover design, the only difference being in the size of the skirt;
FIG. 33 is a side elevational view of a fifteenth embodiment of the flower pot cover design, the only difference being in the size of the skirt;
FIG. 34 is a perspective view of an sixteenth embodiment of our new flower pot cover design;
FIG. 35 is a side elevational view thereof;
FIG. 36 is a top plan view thereof;
FIG. 37 is a bottom plan view thereof;
FIG. 38 is a side elevational view of the design of FIG. 34, the only difference being in the horizontal angle of the skirt;
FIG. 39 is a side elevational view of the design of FIG. 34, the only difference being in the near vertical angle of the skirt;
FIG. 40 is a side elevational view of the design of FIG. 34, the only difference being in the downward angle of the skirt;
FIG. 41 is a side elevational view of a seventeenth embodiment of the flower pot cover design, the only difference being in the height of the base;
- FIG. 42 is a side elevational view of an eighteenth embodiment of the flower pot cover design, the only difference being in the height of the base;
- FIG. 43 is a side elevational view of a nineteenth embodiment of the flower pot cover design, the only difference being in the size of the skirt;
- FIG. 44 is a side elevational view of a twentieth embodiment of the flower pot cover design, the only difference being in the size of the skirt;
- FIG. 45 is a perspective view of an twenty-first embodiment of our new flower pot cover design;
- FIG. 46 is a side elevational view thereof;
- FIG. 47 is a top plan view thereof;
- FIG. 48 is a bottom plan view thereof;
- FIG. 49 is a side elevational view of the design of FIG. 45, the only difference being in the horizontal angle of the skirt;
- FIG. 50 is a side elevational view of the design of FIG. 45, the only difference being in the near vertical angle of the skirt;
- FIG. 51 is a side elevational view of the design of FIG. 45, the only difference being in the downward angle of the skirt;
- FIG. 52 is a side elevational view of a twenty-second embodiment of the flower pot cover design, the only difference being in the height of the base;
- FIG. 53 is a side elevational view of an twenty-third embodiment of the flower pot cover design, the only difference being in the height of the base;
- FIG. 54 is a side elevational view of a twenty-fourth embodiment of the flower pot cover design, the only difference being in the size of the skirt;
- FIG. 55 is a side elevational view of a twenty-fifth embodiment of the flower pot cover design, the only difference being in the size of the skirt;
- FIG. 56 is a perspective view of an twenty-sixth embodiment of our new flower pot cover design;
- FIG. 57 is a side elevational view thereof;
- FIG. 58 is a top plan view thereof;
- FIG. 59 is a bottom plan view thereof;
- FIG. 60 is a side elevational view of the design of FIG. 56, the only difference being in the horizontal angle of the skirt;
- FIG. 61 is a side elevational view of the design of FIG. 56, the only difference being in the near vertical angle of the skirt;
- FIG. 62 is a side elevational view of the design of FIG. 56, the only difference being in the downward angle of the skirt;
- FIG. 63 is a side elevational view of a twenty-seventh embodiment of the flower pot cover design, the only difference being in the height of the base;
- FIG. 64 is a side elevational view of an twenty-eighth embodiment of the flower pot cover design, the only difference being in the height of the base;
- FIG. 65 is a side elevational view of a twenty-ninth embodiment of the flower pot cover design, the only difference being in the size of the skirt; and,
- FIG. 66 is a side elevational view of a thirtieth embodiment of the flower pot cover design, the only difference being in the size of the skirt.
- The flower pot cover has no substantial thickness.

UNITED STATES PATENT AND TRADEMARK OFFICE
CERTIFICATE OF CORRECTION

PATENT NO. : Des. 363,899
DATED : November 7, 1995
INVENTOR(S) : Weder et al.

It is certified that error appears in the above-identified patent and that said Letters Patent is hereby corrected as shown below:

Page 2, after 'FIG. 31 is a side elevational view of', please delete "an", and substitute therefor --a--.

Page 2, after 'FIG. 34 is a perspective view of', please delete "an", and substitute therefor --a--.

Page 2, after 'FIG. 45 is a perspective view of', please delete "an", and substitute therefor --a--.
